UNITED STATES PATENT OFFICE.

OTTO F. FOGELSTRAND, OF KENSINGTON, CONNECTICUT, ASSIGNOR TO HART
MANUFACTURING COMPANY, OF SAME PLACE.

DESIGN FOR A DRAWER-PULL.

Specification forming part of Design No. 5,502, dated January 30, 1872.

To all whom it may concern:

Be it known that I, OTTO F. FOGELSTRAND, of Kensington, in the county of Hartford and State of Connecticut, have invented and produced a new and original Design for a Drawer-Pull, of which the following is a specification:

The nature of my design is fully represented in the accompanying engraving, to which reference is made.

The contour of the face A of the pull is mainly rectangular, with its two upper corners rounded. This face is bordered by a ledge, a, inside of which is raised ornamental scroll-work. The pull has three straight sides and two curved

sides, which, when taken together, assume the same contour as that of the face A, but larger, as the sides are flaring. Each of these five sides are bordered by a ledge, inside of which is a raised ornamental figure. At each end extends a flange, b, in which are the screw-holes.

I claim as my invention—

The design for a drawer-pull, as shown.

OTTO F. FOGELSTRAND.
